(57) **CLAIM**

We claim the ornamental design for an adhesive bandage with decorated pad, as shown and described.

DESCRIPTION

FIG. 1 is a top perspective view of a first embodiment of the present invention;

FIG. 2 is a top view of the adhesive bandage with decorated pad depicted in FIG. 1;

FIG. 3 is a left side view of the adhesive bandage with decorated pad depicted in FIG. 1;

FIG. 4 is a bottom view of the adhesive bandage with decorated pad depicted in FIG. 1;

FIG. 5 is a right side view of the adhesive bandage with decorated pad depicted in FIG. 1;

FIG. 6 is a front side view of the adhesive bandage with decorated pad depicted in FIG. 1; and,

FIG. 7 is a back side view of the adhesive bandage with decorated pad depicted in FIG. 1.

The ornamental design which is claimed is shown in solid lines in the drawings.

The dashed, broken lines in the drawings are shown for the purpose of depicting unclaimed subject matter.
